FREDERICK C. KASCH, OF AKRON, OHIO.

ROOF CONSTRUCTION.

Application filed August 9, 1926. Serial No. 127,990.

The present invention relates to new and useful improvements in roof constructions, whereby an easily assembled, inexpensive design is obtained. The objects of the invention are to produce a simple form of construction which can be laid by one man and can be easily applied to any form of roof construction. It is also an object of the invention to devise a form of roof construction which will not warp or buckle and by which relatively inexpensive material can be used.

These and other objects will be apparent to those familiar with this art. It will be understood that while one form of the invention only is shown, various changes and modifications may be made therein without departing from the essential features thereof as set forth in the appended claims.

In the drawings, in which the form preferred by me at the present time is shown,

Figure 1 is a cross-section through a typical roof construction;

Figure 2 is a transverse section on the line 2—2 of Figure 1;

Figure 3 is a plan;

Figure 4 is an enlarged section of one portion of the roof;

Figure 5 is a plan of the construction at the point of attachment to a purlin; and

Figure 6 is a section on the line 6—6 of Figure 5.

In the construction shown, the numeral 1 represents the purlins supporting the roof structure. Over the purlins is laid the sheet metal 2 which constitutes the basis or foundation of the roof structure. This metal base is provided with a plurality of parallel grooves or channels 3 separated by corresponding ridges 4 connected by inclined walls

5. While the tapering or inclined walls are shown in the various views forming grooves in the general rhomboid configuration, other forms of grooving may be substituted therefor.

In each of the grooves is laid a wooden filler piece 6 of substantially the shape to fit therein, being held in position by any suitable fastening devices, illustrated here as nails 7. It will be observed that the blocks do not fit the grooves tightly, but are cut away at the corners, as shown at 8, to permit the circulation of air through the roof structure, thereby preserving the wood, which may also be creosoted or otherwise treated for the same object. To afford the proper air

circulation, the edges of the sheet 2 may be apertured or cut away in any suitable manner not shown.

The sheets 2 are in standard sizes and are connected along the sides by an overlapping interlocking slide joint, such as shown at 10, so that the sheets may expand and contract. At the ends of the sheets they are overlapped as shown in Figure 6, the blocks 6 terminating short of the sheets so as to permit the overlapping.

At suitable intervals, the structure is provided with means for attachment to the purlins 1. This is done by cutting apertures 11 in the sheets at the edge of the purlin and inserting a fastener at each point. As shown in Figure 6, the fastener 12 is furnished to the workman as an L-shaped strip of metal which is passed down through the aperture 11 and under the flange of the purlin, and then bent over to its final cleating portion as shown in full lines in that figure. This form of fastener is easily applied by one workman and permits expansion and contraction of the sheets. It will be noted that the apertures 11 are somewhat wider than the body of the clip, so that the clips do not interfere with the contraction and expansion of the sheets in a direction parallel to the channels.

At the points where the fasteners are to be applied, the blocks 6 are cut away as shown and after the fastener is applied supplementary blocks 15 are dropped into the grooves over the fastener. These blocks are of the same configuration as the blocks 6, but are cut away at the bottom to accommodate the fastener. The sloping walls 5 support these short blocks adequately.

When the metal base with the filler blocks has been laid over the purlins and fastened in the manner described, a cover 18 is placed over the metal foundation. This may be of any suitable material, but my form of roof structure is particularly adapted for the use of light, cheap and inexpensive material which cannot be used in the prior forms of roof structures.

What is claimed is:

1. In a roof structure, the combination of flanged purlins, foundation sheets comprising a plurality of metal sheets having parallel channels, the sheets being laid over the purlins with overlapping edges parallel to the purlins, clips passed through the bases of the channels and over the flanges of the

purlins, filler blocks of wood in the channels, except at the clips, and shallow additional blocks over the clips.

2. In a roof structure, a foundation of 5 channeled metal sheets, means for fastening such sheets to purlins and to each other so as to permit expansion and contraction, wood filler blocks in the channels, a sheet of roofing material over the metal sheets and secured to 10 the filler blocks, a waterproof covering thereon, and means for securing a circulation of air along the filler blocks.

3. In a roof structure the combination of 15 flanged purlins and a foundation comprising a plurality of metal sheets having parallel

channels, the sheets being laid over the purlins with overlapping edges parallel to the purlins, the sheets being provided with apertures in the bottom of a channel through the overlapped portions arranged in register 20 with the edges of the flanged purlins, and U-shaped metal clips passed through the apertures, one arm of each clip bearing against the underside of a flanged purlin and the other arm bearing against the upper 25 surface of the upper sheet, the apertures being wider than the thickness of the clip so as to permit free contraction and expansion of the sheets.

FREDERICK C. KASCH.
